AUTOMATIC INVERSE FEEDBACK METHOD
AND MEANS FOR CORRECTING RESPONSE
CHARACTERISTIC OF PHOTOTUBE CIR-
CULTS

Norman R. Gunderson, Pasadena, Calif.

Application October 18, 1948, Serial No. 55,034

2 Claims. (Cl. 250—207)

1

This invention pertains to methods and arrangements whereby an electrical circuit or apparatus employing a circuit including a phototube and an amplifier may be automatically corrected for changes in response characteristics of the phototube. More particularly, the invention pertains to methods and means for automatically and periodically correcting and compensating for changes in sensitivity of amplifier systems. Generally, the apparatus of this invention includes an intermittently effective feedback system connected in an inverse or negative feedback sense, and primarily, though not necessarily, intended for use in correcting or compensating for sensitivity drift in an electron multiplier amplifier with or without a phototube input forming an electro-optical system.

The present invention is primarily, though not necessarily, intended for use in automatically compensating for changes in phototube sensitivity in a scanning process, especially in a process in which photographic negatives, positives or other images are scanned. The present invention is described and illustrated in a form employing electron multiplier phototubes of the electrostatically focused type comprising a photosensitive cathode and output anode and a plurality of electrostatic focusing, secondary emission electrodes (commonly known as dynodes), but is not limited thereto since ordinary phototubes may be employed if desired.

Electron multiplier phototubes are subject to a very considerable degree of sensitivity drift during continued operation of the tube although some drift is due to aging. Sensitivity drift due to continued operation is probably caused by a number of cooperating factors such as temperature changes occurring in various elements of the phototube (either self caused by mere operation of the tube or externally caused by variations in ambient temperature), and an inherent instability arising from the mode of operation of such an electron multiplier phototube wherein saturation current flows and relatively little space charge limiting and stabilizing effect is employed.

This sensitivity drift of electron multiplier phototubes has been a major unsolved problem in the art since great advantages would flow from the provision of an electron multiplier amplifier capable of operating in a stable manner and virtually free from sensitivity drift, for a number of reasons, the major one of which is the extreme sensitivity or amplification of an electron multiplier amplifier. Also the space and weight re-

2

quirements are minimized. However, in spite of the extreme sensitivity and high amplification of such phototubes they have not heretofore proved to be satisfactory for use in electro-optical systems intended for use where accuracy is important unless such systems are operative for extremely short periods of time only, in which case the time factor limits the sensitivity drift to a relatively small value. A sensitivity drift compensated electron multiplier phototube amplifier of the type I have invented will find extremely wide application in the art, and indeed will probably replace most ordinary phototubes heretofore used. At the present time I know of no prior art sensitivity drift compensation systems capable of performing the desirable functions of the system of the present invention under the operating conditions met by the system of the present invention.

Generally speaking an illustrative preferred form of the present invention comprises an electron multiplier amplifier system, means for supplying electronic input to the electronic multiplier amplifier, and inverse feedback means responsive to the electron multiplier amplifier output signal arranged to modify the effective amplification of the electron multiplier in a negative feedback sense in accordance with the value of the electron multiplier amplifier output signal whereby sensitivity drift of the system will be minimized. In the preferred form of the present invention means are provided for intermittently and periodically rendering the inverse feedback means responsive to the multiplier output signal whereby the effective amplification of the multiplier will be intermittently modified in a negative feedback sense in accordance with the multiplier output signal during the corresponding intermittent responsive periods. In the preferred form of the invention, the inverse feedback means may be arranged (whenever, during a checking period, the electron multiplier output signal differs from a selected standard value) to modify the amplification of the multiplier in a manner tending to return the multiplier output signal to the selected standard value. When an electron multiplier phototube amplifier of the type comprising a photosensitive cathode, an anode and a plurality of secondary emission electrodes is used, the referencing means may be arranged to periodically and intermittently apply an electric signal of a selected reference value across various or all of the secondary emission electrodes of the multiplier phototube during the simultaneous periods when the inverse feed-

back means is responsive to deviation of the multiplier output signal from the selective standard value and when the referencing means causes modulation of the light input to the photocathode to be of a selected reference value. The inverse feedback means is arranged to modify the standard reference signal applied to the secondary emission electrode in a negative feedback sense thus modifying the amplification of the multiplier in a manner tending to return the multiplier signal to the selected standard value.

The majority of prior art negative feedback amplifiers and closed cycle, negative feedback servomechanisms are of the continuously operating type. That is, they employ continuous negative feedback during operation of the amplifier or servomechanism. Such continuously operating types of negative feedback amplifiers cannot attain as high a degree of sensitivity drift compensation or correction as is possible to attain in an intermittent negative feedback system, such as is employed in the present invention. The reason for this is that the amplified output of a negative feedback amplifier does not precisely correspond in wave form to the input to the amplifier as would occur in an ideal system. Instead a non-linear relationship exists. I have found that this non-linearity is practically eliminated in intermittently effective negative feedback amplifiers.

In addition the method and means of the invention standardize system input modulation momentarily during each intermittent period of negative feedback, which modifies the amplification until the amplifier output reaches a selected standard value equal to some fixed multiple of the amplifier input during each momentary negative feedback amplifier sensitivity drift correction period. This eliminates all of the above mentioned non-linearity in the relationship of amplifier output to amplifier input in a negative feedback amplifier. Thus the present invention provides virtually complete sensitivity drift correction during each intermittent negative feedback period to a degree of accuracy heretofore unattainable even with exceedingly complex, continuous negative feedback amplifiers and servomechanisms.

Since the sensitivity drift in an amplifier, whether of the electron multiplier phototube type or not, is a relatively slow thing, the intermittent correction thereof virtually without error is much more desirable than the continuous relatively inaccurate sensitivity drift correction of an amplifier attainable through prior art systems and methods.

Through the use of the present invention instability and oscillation are avoided and yet during each negative feedback period the sensitivity drift of the amplifier is virtually completely corrected without error in a manner never before attainable.

It should also be noted that the present invention does not apply negative feedback in the customary manner. The negative feedback of the present invention is applied in a manner tending to modify the amplification of the electron multiplier tube in a negative feedback sense, whereas most prior negative feedback systems apply the feedback to the input signal to an amplifier and do not substantially vary the amplification of the amplifier except in rare instances where variable mu tubes have been employed.

It is an object of this invention, therefore, to provide methods and means, including improved negative feedback systems, for virtually completely correcting for changes in response characteristics and sensitivity drift of an electron multiplier amplifier.

A further object of the present invention is to provide an improved negative feedback system for use with an electron multiplier amplifier to intermittently apply negative feedback to the multiplier in a manner modifying the amplification of the multiplier to intermittently correct sensitivity drift in the amplifier.

Other and allied objects will be apparent to those skilled in the art from a careful study of the illustrations, specifications and appended claims. To facilitate understanding reference will be made to the following drawing in which:

Fig. 1 illustrates one embodiment of the present invention employed in conjunction with a logarithmic amplifier system of the general type more particularly described and claimed in my co-pending, allowed patent application, Serial No. 702,172, filed October 9, 1946, now Patent No. 2,454,871, and also described and illustrated in my Patent No. 2,413,706 in conjunction with a mechanically driven scanning drum adapted to carry a photographic negative or positive, or other image to be scanned by the photocathode of the electron multiplier phototube forming part of the logarithmic amplifier.

Fig. 2 is a graph illustrating the relationship of output current to potential difference between the last dynode and the anode of an electrostatically focused secondary emission electron multiplier tube of a type such as an R. C. A. 931 multiplier phototube.

Fig. 3 is a diagrammatic electrical schematic drawing of a second illustrative form of the present invention.

The example, Fig. 1, shows an electron multiplier amplifier provided with means for introducing an electronic input thereto and secondary emission controlling means. The specific form of electron multiplier amplifier shown in Fig. 1 is of the type wherein the electronic input is provided by a photosensitive cathode 2 of multiplier phototube 1 and wherein the secondary emission controlling means comprises a plurality of secondary electron emission controlling electrodes (commonly known as dynodes) indicated generally at 97. The output anode of the multiplier phototube 1 is indicated at 3. The series of secondary electron emission electrodes 97 are connected at spaced points along a resistor 4 through which a controlled electric current passes, thus applying the proper potential to each of the secondary emission electrodes 97 for controllably producing secondary electron emission from each of said electrodes and electrostatically focusing the emitted electrons upon the succeeding secondary emission electrode. The original source of electrons is the photosensitive cathode 2 which emits electrons in response to light input thereto, which are electrostatically focused upon the adjacent, succeeding secondary emission electrode, the secondary emission electrode immediately adjacent the anode 3 electrostatically focusing the electrons emitted therefrom upon the anode 3. One form of such electron multiplier phototube is the R. C. A. 931 manufactured by the Radio Corporation of America.

The bleeder resistor 4 is connected in series with a rectifier tube 9, terminal 6 of power supply

7, and a variable potentiometer indicated generally at 51, the opposite ends of which are connected to terminals 5 and 53 of the power supply 7. Terminal 5 may be at 150 volts negative potential with respect to ground, and terminal 53 may be at 200 volts negative potential with respect to ground. The positive terminal 8 of the power supply 7 is grounded, thus connecting the resistor 4 in series with an electron tube 26 through the cathode 27 thereof which is also grounded. The anode 28 of tube 26 is connected to the positive terminal 29 of a power supply 30. The power supply 30, in the example illustrated, is of 1400 volts potential (which is considerably greater than the potential supplied by the power supply 7) so that normally the anode of the rectifier power tube 9 is negative with respect to the cathode thereof, thus allowing no current to pass through the circuit comprising the rectifier tube 9, the resistor 4, the potentiometer 51 and the power supply 7. The only current that normally flows through the resistor 4 is that which flows from the power supply 30 through the resistor 4 and through the potentiometer 51 through a portion of the power supply 7 to the grounded terminal 8 thereof, through the cathode 27 of the tube 26 to the anode 28 thereof and back to the positive terminal 29 of the power supply 30. Since this current flows through the tube 26 it can be seen that the current normally flowing through the resistor 4 (and therefore the potentials applied to the secondary emission-controlling electrodes 97) is controlled by the bias of grid 25 of tube 26.

The effective overall amplification of a multiplier tube of the type illustrated at 1 is controlled by the potentials applied to the secondary emission controlling electrodes 97, and therefore the amplification of the electron multiplier phototube 1 is controlled by the bias of grid 25 of the electron tube 26 and also by the setting of the potentiometer 51. However, since the potentiometer setting is fixed during normal operation of the system and is changed only during intermittent, periodic sensitivity drift correction periods it can be ignored as far as transient variations in the amplification of the multiplier tube 1 are concerned. The potentiometer 51 comprises part of the inverse feedback means and will be more fully described hereinafter.

Output anode 3 of phototube 1 is connected through a resistance 10 to the positive terminal 31 of a power supply 28', which is grounded at 32. In the example terminal 31 of power supply 28', is at 300 volt positive potential with respect to ground. Anode 3 is also connected to grid 11 of an electron tube 12, whose cathode 13 is grounded and whose anode 14 is connected through a resistance 15 to terminal 31 of power supply 28'. Anode 14 of tube 12 is also connected through a resistance 16 to the grid 18 of an electron tube 19, the cathode 20 of which is grounded and the anode 21 of which is connected through a resistance 22 to the positive terminal 31 of the power supply 28. The lower end of the resistor 16 and the grid 18 are connected through a resistance 17 to the lower terminal 31' of power supply 28' which terminal 31' is at a negative potential of 300 volts. The lower end of the resistor 16, the upper end of the resistor 17 and the grid 18 of tube 19 are connected through a resistor 33 and junction 50 to inverse feedback means which will be more particularly described hereafter.

Electron tube 19 is provided with anode 21

connected through a resistance 23 to grid 25 of tube 26 and through a resistor 24, to the negative terminal 31' of the power supply 28'. The lower end of resistor 22 is also connected to the anode 200 of an electron tube 201, the cathode 202 of which is grounded and also connected to a switch 203 arranged to controllably make contact with contact 204 connected to the grid of the tube 201. The grid and the contact 204 are also connected through a resistance 205 to a terminal 206 which is connected to the negative terminal of a low voltage power supply 206' (such as -15 volts).

From the above description it can be seen that the output of the electron multiplier phototube 1 is resistively coupled to the succeeding amplifier stage including electron tube 12 which is resistively coupled to the succeeding amplifier stage including tube 19 which is resistively coupled to the succeeding amplifier stage including the tube 26, and that the output of tube 26 (which corresponds to the output of the multiplier tube 1) controls the current flow through the resistor 4 and consequently the potential across the dynodes of the electron multiplier tube 1, thus controlling the amplification constant thereof in an inverse feedback manner tending to maintain the anode output current of the electron multiplier tube 1 virtually at a constant value, irrespective of light input to the photocathode 2 of the multiplier. The voltage applied across the bleeder resistor 4 (which can be picked off at the output terminal 49) has a virtually logarithmic relationship to the light input to the photocathode 2. The operation of the logarithmic amplifier is more fully described in the hereinabove-mentioned copending allowed patent application Serial No. 702,172, filed October 9, 1946, now Patent No. 2,454,871, and need not be described in detail herein.

The input to the system (in the example illustrated in Fig. 1) is preferably in the form of light modulations produced by a driven scanning drum carrying a photographic negative, positive, or any other suitable image to be scanned, which is arranged to modulate a scanning light beam produced by the lamp 47. The mechanically driven scanning drum and image carried thereby are not shown in Fig. 1 since they are well known in the art and are shown in the hereinbefore-mentioned Patent No. 2,413,706.

Referencing means are provided to intermittently apply a selected reference voltage or signal to the secondary emission electrodes 97 during short duration, periodic checking or correction periods. In the example this includes the tube 201 which is connected in parallel with tube 19. Switch 203 is arranged to close under the control of motor 251 receiving power from leads 252. Motor 251 drives the scanning drum hereinabove mentioned (not shown). The closing of switch 203 removes negative bias from the grid of the tube 201 and allows same to conduct electric current therethrough and causes grid 25 of tube 26 to become extremely negative with respect to ground and to prevent the flow of current through the electron tube 26 and consequently through the resistor 4. Since the plate of tube 9 is no longer negative, tube 9 will become conductive, thus applying a constant preselected reference signal from power supply 7 to the secondary emission electrodes 97 (modified, of course, by the setting of the potentiometer 51) during the intermittent periods when the switch 203 is in contact with the electric contact point 204.

Motor 251 driving the scanning drum (not shown) is also arranged to close the switch 43 simultaneously with the closure of switch 203, and the image carried by the scanning drum or the scanning drum itself is provided with a strip of constant optical density in a position such as to modify the modulation of the light originally emitted by lamp 47 to a selected reference value during the period of time when the switches 203 and 43 are closed, whereby the modulation of the light input to the photocathode 2 of the phototube 1 will be of a selected reference value intermittently at precisely the same period that a selected fixed reference value potential or signal is applied to the secondary emission electrodes 97 and at the same period that the switch 43 is closed to render the inverse feedback means responsive to variations in the amplified phototube output current.

The inverse feedback means used during the intermittent adjusting period includes an electron tube 35, the grid 34 of which is connected through a junction 58 to the output of electron tube 12. In this way the output voltage of tube 12 controls the current through tube 35 and through coil 38 of a relay indicated generally at 38'. The relay coil 38 controls the position of switch arm 39 positioned between two electric contacts 40 and 41. If the current through tube 35 and relay coil 38 is greater than the closing current of the relay, then connection will be made between contacts 39 and 41 and the motor will be caused to rotate in one direction. If the current through tube 35 and relay coil 38 is less than the opening current of the relay then connection will be made between contacts 39 and 40 and the motor will be caused to rotate in the opposite direction. Due to the amplifying action of tubes 35 and 12 a very small voltage change at the grid of tube 12 is sufficient to change the position of the relay armature. During the intermittent adjusting period the current from anode 3 of phototube 1 is such as to cause a voltage drop in resistor 10 slightly greater than the positive potential above ground of the terminal 31 of power supply 28'. In the example given the voltage of terminal 31 is +300 volts with respect to ground. If the current from anode 3 of phototube 1 decreases by a very small percentage from the mean value for correct adjustment, then the grid of tube 12 will be made more positive than the mean value for correct adjustment. The anode 14 of tube 12 and the grid 34 of tube 35 will in turn be made more negative than their respective mean values. The relay 38' will be de-energized and connection will be made between contacts 39 and 40. This causes the motor 42 to rotate in such a direction that potentiometer 54 increases the voltage impressed on multiplier section 4 of phototube 1 by power supply 7. The opposite action takes place if the current from anode 3 of phototube 1 is greater than the normal mean value during the automatic adjusting period.

The method of operation of the example described hereinabove should be readily understood but may be reviewed here. It will be noted that during scanning (as for example, at the end of every other line of scan, or at any other desirable but frequently repeated time period) a number of operations simultaneously take place during a momentary period of time, whereby the amplifier is checked and corrected. These simultaneous operations include

(a) Closure of switch 203 to block tube 26

and interrupt the amplifier, thereby applying a fixed reference value signal to the secondary electrodes 97 (as modified by the setting of potentiometer 51);

5 (b) Modification of light from scanning lamp 47 to a selected value (as by the optical strip on the scanning drum, or other suitable means);

(c) Closure of switch 43 to supply energy to motor 42 under the control of relay 38.

Rotation of motor 42 is translated into an adjustment movement of potentiometer 51 to modify the reference signal applied to secondary emission electrodes 97 in a negative feedback sense until the multiplier tube output signal returns to the preselected standard signal. Thus the system provides for a standard input modulation during the checking period, the application of a reference signal to the secondary emission controlling means and means for modifying the reference signal applied to the secondary emission controlling means in a negative feedback sense in response to deviation of the output signal from a standard value during the checking period, until such time as standard value is reached by the output signal. Thus during each checking or adjusting period the sensitivity drift of the electron multiplier amplifier is virtually completely corrected.

Adjustment of the setting of potentiometer 51 by the motor 42 during the adjusting periods acts to vary the potential applied across resistor 4 in a manner which varies the amplification of the electron multiplier tube 1 by varying the potential across the dynodes 97. However it also acts to vary the potential between the last dynode and the anode 3 of the electron multiplier phototube. As can be seen from examination of Fig. 2 when the voltage between the last dynode and the anode falls between certain limits defined by the curves shown in Fig. 2, virtually no variation in output current of the phototube occurs as a result of variations in the potential existing between the last dynode and the anode. Thus variations in the setting of the potentiometer 51 act to produce potential variations across the dynodes which affect the amplification constant of the tube in such manner that the voltage variations existing between the last dynode and the anode of the multiplier tube have virtually no effect on the output current of the multiplier tube.

Fig. 3 illustrates (in fragmentary form) a slight modification of the form of my invention shown in Fig. 1 wherein a variable rheostat 51' is substituted for the variable potentiometer 51 of Fig. 1. The balance of the components shown in Fig. 3 are indicated by primed reference numerals similar to those used to indicate corresponding components in Fig. 1. The operation of the device is quite similar to that shown in Fig. 1 and need not be described specifically.

It should be noted that the examples described and illustrated herein are illustrative only and numerous modifications within the scope of the present invention will occur to those skilled in the art, and all such are intended to be included and comprehended herein. For example: the secondary emission controlling electrodes need not be simultaneously varied in potential to produce a variation in the amplification of the multiplier tube. Under some circumstances it may be desirable to vary the potential between two or more of the dynodes rather than across all the dynodes. Although the amplifier illustrated in Fig. 1 is of the logarithmic type, the method

and means of this invention can be applied to any amplifier employing a multiplier phototube, including an antilogarithmic amplifier of the character illustrated and described in my copending application Serial No. 55,033, filed concurrently herewith.

While the present invention has been described in connection with an electron multiplier amplifier having a photocathode arranged to provide an electronic input to the secondary emission controlling means in response to light impinging the photocathode, it is to be understood that the invention is not limited to this arrangement, since any type of electronic input to an electron multiplier tube could be substituted for the photoelectric input. For example, the electronic input to the secondary emission controlling means might be of a thermionic type, or various other types of electronic input may be employed with the present invention. While the present invention is described as employing secondary emission electrodes, it is not limited to such an arrangement, since any type of secondary emission controlling means may be employed. For example, magnetic electron focusing and/or secondary emission controlling means may be employed, singly or in conjunction with electrostatic secondary electron emission controlling and/or focusing means.

The referencing means may also be modified within wide limits without departing from the spirit of the present invention. Any means for providing intermittent fixed reference modulation of system input and simultaneous inverse feedback to the amplifier for causing the modification of the amplifier output to a fixed standard bearing a certain preselected relationship to the fixed selection reference input modulation may be employed. Numerous types of inverse feedback means may be employed.

The inverse feedback may be applied to the electronic input to the multiplier or to the light input to a photoelectric electronic multiplier tube rather than to the secondary emission controlling means, if desired. This is more particularly described, illustrated and claimed in my copending application Serial No. 55,033, filed concurrently herewith.

I claim:

1. In an amplifier system including an electron multiplier phototube having a cathode, an anode, and a plurality of dynodes, a voltage supply for said dynodes and an output, the provision of means arranged to automatically correct for changes in effective amplification of the phototube, said means comprising: means for supplying light to the phototube; an inverse feedback adjustment means responsive to the output anode current of the phototube and arranged to modify the effective amplification of the phototube; means for frequently rendering the feedback adjustment means effective for periods of short duration; and means for restoring light input to the phototube to a constant value expected to produce an output anode current of selected value during said periods, said feedback adjustment means being arranged to adjust the voltage supplied to the dynodes of the phototube by maintaining the said cathode at a constant potential and varying the potential applied to said dynodes in accordance with the deviation of the output anode current obtained during said period from the output anode current of selected value.
2. A system of the character stated in claim 1, wherein the inverse feedback means includes a reversible motor; a variable resistance means operably controlled by the motor and operably connected to the voltage supply to the dynodes of the phototube; a reversing switch means for energizing the motor in either direction; and relay means, responsive to deviation of the output anode current of the phototube during an adjusting period from the output anode current of selected value, for actuating the switch means.
